(57) **CLAIM**

The ornamental design for a ribbon flag, as shown and described.

DESCRIPTION

FIG. 1 is an environmental perspective view of the ribbon flag.

FIG. 2 is an environmental perspective view of the ribbon flag; and,

FIG. 3 is a top view of the ribbon flag.

The broken lines in the drawings represent environmental subject matter that forms no part of the claimed design.

1 Claim, 3 Drawing Sheets

FIG. 1

FIG.2

FIG.3
